GAUGE CASING

Ted A. Bell, Pittsburgh, Pa., assignor to Dresser
Industries, Inc., Dallas, Tex.

Filed Jan. 5, 1971, Ser. No. 104,202

Term of patent 14 years

Int. Cl. D10—04

U.S. Cl. D52—6

FIG. 1

FIG. 3

FIG. 4

FIG. 2

FIG. 5

FIG. 1 is a front elevational view of gauge casing showing my new design;

FIG. 2 is a rear elevational view thereof;

FIG. 3 is a side elevational view thereof;

FIG. 4 is a top plan view thereof; and

FIG. 5 is a bottom plan view thereof.

I claim:

The ornamental design for a gauge casing, as shown.
